UNITED STATES PATENT OFFICE.

DONALD H. PARCE, OF OAKLAND, CALIFORNIA.

LAUNDRY-DISTRIBUTING SYSTEM.

1,217,986.

Specification of Letters Patent. Patented Mar. 6, 1917.

Application filed June 24, 1914. Serial No. 847,016.

To all whom it may concern:

Be it known that I, DONALD H. PARCE, a citizen of the United States, residing at 5662 Ocean View Drive, Oakland, in the 5 county of Alameda and State of California, have invented certain new and useful Improvements in Laundry-Distributing Systems, of which the following is a specification.

10 This invention relates to improvements in laundry distributing systems and has special reference to a method of separating the laundried articles so that those of the same lot are placed in the same receptacle 15 and each lot in a separate receptacle.

The principal object of my invention is to provide means to eliminate the marking of each article, and the hand sorting thereof. At the present time articles of this class 20 known as rough dry are either marked with ink and then the articles sorted into bins or a numbered pin is attached to each article which remains on the same during the washing operations and is removed as the article 25 is sorted and stacked in the correspondingly numbered bin. These bins are arranged in vertical rows and it will be readily appreciated that in order to keep them at a reasonable height the length is so great that 30 considerable time is lost in walking from one bin to another and in removing articles from such bins.

With my improved device a pin bearing a designating number is attached to each 35 article of a lot and after the washing and drying operations, this pin is placed on a moving conveyer and the pin and attached article dropped into a correspondingly numbered bin. I prefer to construct these bins 40 at a sufficient distance from the floor to enable a person to walk underneath and a door to be placed in the bottom of each bin through which the articles may be quickly emptied.

45 With these and other objects in view my invention consists in the novel construction and arrangement of parts as herein described and as more specifically pointed out in the appended claims.

50 Reference being had to the accompanying drawings forming a part of this specification wherein,

Figure 1 is a view in perspective of my improved sorting conveyer showing the 55 same arranged above the bins into which the articles are dropped and the table from

which the garments are placed in the conveyers.

Fig. 2 is a fragmentary view taken above one of the row of bins showing the manner 60 in which the conveyer track is constructed to cause the pins to drop into the corresponding bin.

Fig. 3 is a modified form of a conveyer track used in order to insure the dropping 65 of the pins about central with the bin.

Fig. 4 is an enlarged view in section through the conveyer showing the pin being conveyed along the track thereof and a fragment of garment attached thereto. 70

Fig. 5 is a view in perspective of the cable attachment by which the pins are moved along the conveyer.

Fig. 6 is a view in end elevation of the cam by which the feed mechanism is operated. 75

Fig. 7 is a view in plan of the feed end of one of the conveyers.

Fig. 8 is a view in end elevation of one conveyer and its feed. 80

Fig. 9 is a view in side elevation further illustrating the same mechanism.

Fig. 10 is a view in end elevation of the feed track.

Fig. 11 is a detail view of the pin which 85 is attached to the garments before the laundry operations are commenced.

Fig. 12 is a view of a modified form of the same.

Fig. 13 is a plan view, partly in section, 90 of the feed mechanism.

Referring to corresponding parts in the several views by the same numerals of reference, 1 denotes in general my improved conveyers which, as in Fig. 1, are shown 95 suspended above the opened top receptacles or bins 2, and in large installations it is generally necessary to provide several rows of these receptacles with a conveyer located centrally over the top of each. A 100 table or other receptacle on which the unsorted garments are placed within convenient reach of the operator is denoted by 4 and this table may be located on a platform 5 made some distance above the floor of the 105 laundry building. The conveyers 1 are made to converge toward this table as shown at 3, so that the operator may reach any one without moving from a fixed position. The receptacles 2 are preferably constructed 110 of a light steel frame covered with wire netting. A walk 6 is provided along the sides

of the group of receptacles, which is connected with the platform 5, enabling the operator by means of a pole to reach over the receptacles in order to withdraw a garment which has fallen on a division wall between two receptacles.

The conveyers consist of longitudinally spaced bars of standard structural shapes, as here shown, bottom angles 7 and upper angles 8, these angles being connected by means of vertically disposed bars 9 riveted to the side flanges of the upper and lower angles. The bars 9 on the two sides of the conveyer are spaced directly opposite one another and are connected by means of a threaded pin 10 having nuts 11 on the inside and outside of each bar, thus enabling the width between the angles to be accurately spaced. At suitable intervals certain of these vertical bars are extended upwardly as shown at 12 and by these extended bars the conveyer is supported to the ceiling or other suitable structure.

The pin which is attached to the garments consists of the usual form of safety pin, which I denote by 13 and to the coiled end thereof is attached a member 14 consisting of a disk 15 and contracted neck 16 having projecting lugs 17 and 18, which are bent over the pin to hold the member to the pin, lug 18 being bent loosely around the coiled end of the pin to allow movement of the latter when the pin is opened or closed. On the sides of this neck are laterally projecting lugs 16', the use of which is hereinafter explained.

The disks 15 are of varying diameters, each diameter being given a separate number, as shown at 19. Also a second designation 19' is placed on these disks, which designates the conveyer track on which that particular disk is to be handled, the numbers on the disk running consecutively from 1 upwardly and the bin being correspondingly numbered. Thus the first conveyer may handle disks numbered 1 to 16 and the bins under this conveyer being correspondingly numbered. The second conveyer would handle a set of disks having the same graduations in diameter, but having a different designation 19' to indicate that this disk was to be placed on the second conveyer. The numbers on this disk would be 17 to 32 and the bin thereunder correspondingly numbered. If the disks 15 are of varying diameters and the longitudinal lower bars 7 are divergently spaced as shown in Figs. 2 or 3 and the disks moving along the upper surface of this track are held by suitable means at a fixed angle to the upper surface and to the edges of this track, it will be evident that the smaller size disks will drop into the first receptacle 2, the next size will drop into the next receptacle and so on until the end of the con-

veyer is reached. The disks may be made circular as shown in Fig. 12, or with angular sides as shown in Fig. 11.

With a trackway of this type the angles being uniformly divergent, a slight variation in the width of the slot or the diameter of the disk would cause the latter to drop through at some point other than the center of the bin and to obviate this difficulty the track may be made with a slot between with a series of steps, as shown in Fig. 3, in one or both angles.

At the ends of the conveyer are pivotally mounted grooved wheels 20 and 20', the latter designating the driving wheel and the former wheel adjacent the feed end. I prefer to use a cable 21 in order that the conveyer may turn in a horizontal as well as a vertical direction but a belt or chain may be used. The type of attachment which I use to move the disks along the slot in the conveyer track and at the same time hold these disks perpendicular to the said slot is shown in detail in Fig. 5. The attachment 29 consists of two similar halves joined at 22 to prevent the halves separating longitudinally or moving angularly with respect to each other. Each half is punched and bent from a single piece of metal and consists of the portion 23 adapted to fit around the cable, the end of said portion being continued in the triangular depending ends 24, the edges having wings 25 bent at right angles to said triangular ends and having the lower ends of lesser width as shown at 26. These halves are held on the cable by rivets or screws 27, the wings being so formed that a space 28 is secured between the wings of the adjacent halves.

The manner in which the pins are automatically fed into the space 28 is shown in detail in Figs. 7 to 10 inclusive. Adjacent wheel 20, is a revoluble bar 30 having the angularly projecting ends 31 diametrically disposed and adapted to project in the path of the attachment 29. This bar is formed on a sleeve 32 which extends through the bearing 33 and is provided with a beveled gear 34 on the outer end thereof. This gear meshes with the corresponding toothed gear 35 having one half the pitch diameter so as to make one revolution to a half revolution of bar 30. Gear 35 is mounted on shaft 36 on the opposite end of which is a cam 37. This cam contacts with the lever arm 38 attached to the vertical shaft 39, said shaft extended through a suitable bearing 40 and underneath the lower angle 7 has attached a second lever bar 41. The disks with the pins are placed in the inclined trackway 42, which is pivotally mounted as shown at 43 and spring 44 being adapted to hold the same normally in its left hand position. This trackway consists of the groove 45

slightly wider than the disks are thick so that the same cannot overlap in feeding down the trackway. The enlarged portion 46 is provided for the projecting lugs 16' which prevent the disk from dropping through the trackway.

Attached to the frame of the conveyer at the lower end of the track is a stationary bar 50 which, when 42 is to the left, serves 10 as a stop for the neck of the pin when the latter reaches the bottom of the inclined trackway. The ends of the inclined trackway are extended under the conveyer, the one side to be terminated as shown at 42'. 15 To prevent the pins feeding while one is being fed into the conveyer by arm 41, a spring actuated stop pin 51 is provided which projects across the path of slot 45 when the member 42 is in its right hand position. 20 This pin is pushed outwardly by a spring 51' so that in case the end thereof contacts with a disk when the track is moving to the right the pin can move and prevent undue strain. Spring 51' abuts against 9' 25 and a pin 51^b, a head 51^a limits the action of this spring.

Pivottally mounted on the end 42 is a latch bar 50', the upper end of which is extended into the path of the clip 29 by means of a spring 61. The lower end of this latch bar is adapted to contact with the raised lip 54 on the outer end of bar 41.

The use and operation of this device is as follows:

35 The pins 13 are attached to the articles to be laundried when the same are received, each lot of the apparel bearing a separate number. These pins remain on the articles during the laundrying operation when the 40 various lots become mixed together. In this condition the articles are placed on the sorting table, the operator picking up each garment separately by the designating pin placing the latter in the proper feed track 42, this track being indicated by the designation 19'. It will be understood that the reason for having the latter designation on the 45 enlarged head of the pin is: that the number of sizes of the heads may be kept to a minimum and the variations between sizes at a maximum, which does not necessitate such accurate adjustment of the track slot. When the pins are placed on the inclined trackway the head portion enters slot 45 with the lateral extending lugs 16' resting on a bottom of the groove 46 and so prevent the pin from dropping through the open slot in the bottom. These pins with their 50 attached articles slide by gravity down this track, the lowermost pin contacting with the stop 50.

Now, as the cable 21 rotates one of the attachments 29 contacts with the upper end 31 of bar 30 and rotates the same to the position shown in Fig. 9. This rotation causes

one revolution of cam 37, which brings the high point to the position shown in Fig. 9. Just before this cam reaches this position the catch 50' engages the side of the same attachment and causes the trackway 42 to move about the pivot 43 at the same speed that the cable is traveling. As the track moves to the right the lowermost pin is freed by the stop arm 50 and at the same time the stop 51 enters between the pin and the following one, as is clearly illustrated in Fig. 8. When the track reaches the limit of its travel to the right the arm 38 is released by the projecting end of the cam allowing the same to be pulled in to the lower portion by means of the spring 38'. The movement of arm 38 is transmitted through the shaft 39 to the arm 41, which extends across the path of the shank 16 of pin extension, and the latter is thus forcibly moved into the slot 28 between the two parts of the attachment 29 with which 31 and 50' are engaged. When 41 has moved to approximately its limit the projected lug 54 engages the bottom of spring catch 50' throwing the upper end thereof out of engagement with the attachment 29, thus releasing this end of the inclined trackway allowing the spring 44 to return the same to its left position. When in the latter position the following pin head is free to slide downwardly past the projecting end of pin 51, past the end of the lever arm 41, and is positioned by the stop 50. In the meantime the arm 30 is rotated a sufficient amount to enable its end 31 to clear the attachment. The disk like portion of the pin attachment is then moved along the trackway formed by the lower angles 7, being held in a fixed position until the slot has widened a sufficient amount to allow the same to drop through. As all pins bearing the same designation 19 and 19' drop through the conveyer at the same point and as these pins belong to the same lot of apparel it will be apparent that all these articles will be dropped in the same bin.

While I have shown the preferred embodiment of my invention it will be understood that various changes in form and minor details of construction may be resorted to without departing from the scope of the claims.

What I claim as new and wish to cover by Letters Patent is:

1. Sorting apparatus, comprising identifying means attachable to the articles to be sorted, conveying means for moving said articles, and means for releasing said identifying means from said conveying means at predetermined points.

2. In an apparatus for distributing articles, a trackway, and means for segregating and identifying said articles, said means being attachable to said articles and movable along said trackway.

3. In a laundry sorting machine, a trackway having a slot of varying width and identifying means attachable to pieces of laundry and slideable in said slot.
4. In a laundry sorting machine, a trackway having a slot of varying width and identifying means attachable to pieces of laundry slideable in said slot, said slot arranged to drop said identifying means at predetermined points.
5. In a sorting apparatus a trackway having a slot of varying width, identifying means attachable to the articles to be sorted and slideable in said slot, said slot arranged to release said identifying means at predetermined points, and receptacles to catch said released means and articles.
6. In a laundry sorting machine, a track, identifying means attachable to pieces of laundry slideable on said track, and means for propelling said identifying means along said track, said track being arranged to drop said identifying means at predetermined points.
7. In a laundry sorting apparatus, a trackway, identifying means attachable to individual pieces of laundry slideable on said trackway, means for propelling said identifying means along said trackway, and means in said trackway for releasing said identifying means from the trackway.
8. A device for the purpose described comprising, a cable conveyer, trackways below said cable, said trackways being spaced apart to form a diverging slot centrally below said cable, attachments on said cable adapted to hold a disk perpendicular to said trackways, a disk, a reduced neck portion on said disk, and a spring closed pin attached to said reduced portion.
9. A device for the purpose described comprising, a conveyer, trackways adjacent said cable, said trackway being spaced apart to form a divergent slot, attachments on said cable adapted to hold a disk at a fixed angle to said trackways, metallic disks of varying diameter, a reduced neck portion extending from said disk adapted to extend through the divergent slot, a spring pin attached to the end of said reduced neck portion and lateral lugs formed on said neck portion.
10. A device for the purpose described comprising a conveyer, divergent trackways adjacent said conveyer, disks of varying diameter adapted to be moved along said trackways, and clips carried by said conveyer for moving said disks.
11. In a laundry sorting machine a trackway having a diverging slot, identifying means attachable to pieces of laundry and slideable in said slot, and means for causing said identifying means to move along the trackway.
12. An article for the purpose described comprising a disk, means for securing an article to the disk, said disk provided with one or more identifying marks, an extension on said disk, means carried by said extension for attaching the same to said securing means, and laterally extending supporting lips of said extension.
13. In a laundry sorting machine a trackway having a slot of varying width, identifying means of corresponding various widths attachable to pieces of laundry slideable in said slot, and means for moving said identifying means along said trackway.
14. A device of the character described comprising, in combination with trackways forming a diverging stepped slot, disks having varying diameter and adapted to be moved along said trackways, and clips movable parallel to the said trackways adapted to hold said disks at a constant angle to said trackways.
15. A device for the purpose described comprising, metallic trackways, said trackways being spaced apart to form a diverging slot parallel to said cable, adjusting bolts for maintaining correct divergence, disks of varying diameter adapted to be attached to the article to be sorted, and means for moving said disks along said trackways.
16. A device for sorting articles comprising, in combination with bins to receive the sorted articles, trackways forming a diverging slot, disks of varying diameters attached to the articles to be sorted, and means for moving said disks along said trackways.
17. In an apparatus for distributing articles, a trackway and means for carrying, segregating and identifying said articles, slideable on said trackway.
18. In a sorting machine, a trackway, and article carrying and identifying means slideable on said trackway, said trackway adapted to drop said carrying and identifying means at predetermined points.
19. The combination with a moving conveyer and attachments therefor, of a feed track, said track being oscillatably mounted about a point removed from said conveyer, a spring catch adapted to engage the attachments of said conveyer to move said track in the direction of travel of said conveyer, and spring means for returning said track to its normal position.
20. The combination with a moving conveyer and attachment thereon, of a member adapted to be moved along said conveyer by said attachment, means for positioning said members for feeding into said conveyer, a revolute bar the ends of which are adapted to engage said attachments, a cam driven by said revolute bar, and a lever arm operated by said cam to move said members into engagement with said attachments.
21. The combination with a moving conveyer and attachments thereon, of an inclined pivotally mounted feed track, secur-

ing means adapted to slide down said track, means for moving the end of said track adjacent said conveyer in the same direction and at the same speed when said track is opposite one of said attachments, a stop bar adapted to position said securing means before the movement of said track takes place, means operated by the attachment opposite said feed track for transferring said securing means from said track to said attachment after said track has moved a sufficient distance to allow said securing means to clear said stop, and a spring pressed stop pin adapted to prevent feeding of the following securing means while said first mentioned securing means is being transferred to said attachment.

22. The combination with a conveyer and attachments therefor, of securing means adapted to be moved along said conveyer by said attachments, an oscillatable inclined feed track, means carried by said feed track for engaging said attachments and moving said track in unison with said attachment during the feeding operation, means carried by the feed bar for releasing said attachment engaging means when said securing means has been fed, and spring means for returning said inclined track to its normal position.

23. A device of the character described comprising the combination of a conveyer, diverging trackways adjacent said conveyer, attachments on the flexible band of said conveyer, disks adapted to be moved along said trackway by said attachments, an inclined feed track for said disks and means operated by said attachments for transferring said disks from said feed track to said diverging trackway.

24. A device as described comprising a cable conveyer, a trackway spaced adjacent said conveyer, the edge of said trackway being stepped to form a diverging slot and identifying and carrying means attachable to the articles to be sorted slidable in said slot.

25. In a sorting machine a trackway, article segregating and identifying means movable on said trackway and means for propelling said means along said trackway, said trackway arranged to release and drop said means at predetermined points.

26. In a sorting machine a trackway, article carrying and identifying means movable on said trackway and means for propelling said carrying and identifying means along said trackway, said trackway being formed to drop said carrying and identifying means at predetermined points.

27. In a sorting machine, a trackway having a slot of varying width, article carrying and identifying means of corresponding various widths slidable in said slot, and means for propelling said carrying and identifying

means along said slot whereby they are released from the slot when they reach a portion of corresponding width.

28. In a sorting machine a trackway, carrying segregating and identifying means 70 slidable or said trackway, means for moving said carrying means along the trackway, means for feeding said carrying means to said trackway and means for operating said feed means.

29. In a sorting machine, a structure having a slot of three or more different widths, carrying and identifying means of corresponding different widths slidable in said slot, mechanism for inserting said carrying and identifying means in said slot and means for sliding said carrying and identifying means along said slot.

30. In a sorting machine, a structure having a slot of three or more different widths, carrying and identifying means of corresponding different widths slidable in said slot, a conveyer for sliding said carrying and identifying means along said slot, and means operated by the movement of said conveyer 90 for introducing said carrying and identifying means into said slot.

31. In a sorting machine a main trackway, article carrying and identifying means slidable on said trackway, means for propelling said carrying and identifying means along the trackway, a feed trackway adjacent the main trackway for holding said carrying and identifying means, and automatically operated mechanism for transferring 100 the carrying and identifying means from said feed trackway to said main trackway.

32. In a sorting apparatus, a trackway having a slot of progressively increasing width, identifying means attachable to the 105 articles to be sorted and slidable in said slot, means for propelling said identifying means along said trackway, means for releasing said identifying means from the slot at predetermined points and means adjacent said 110 points for receiving said released identifying means.

33. In a sorting machine, a structure having a slot of varying width, article supporting and identifying means of corresponding 115 widths movable in said slot, a feed structure for holding said supporting and identifying means, and automatically operated mechanism for transferring the supporting and identifying means from the feed structure 120 to the slot, and means for conveying said supporting and identifying means along the slot.

34. In a sorting machine a trackway, segregating and identifying means movable on 125 the trackway, mechanism for moving said means along the trackway, automatically operated means for introducing said first named means to said trackway, and automatically operated means for releasing said first 130

named means from said trackway at predetermined points.

35. In a sorting machine, a trackway, identifying means slidable on said trackway, 5 an endless conveyer arranged adjacent said trackway having means thereon for engaging said identifying means and means for driving said conveyer.

36. In a sorting machine a trackway, segregating and identifying means movable on 10 said trackway, an endless conveyer arranged adjacent said trackway having means thereon adapted to engage and move the segregating and identifying means along the 15 trackway and means for driving said conveyer, said trackway being arranged to release said segregating and identifying means at predetermined points.

37. In a sorting machine, a structure having 20 a slot of progressively increasing width, carrying and identifying means slidable in said slot, a conveyer adjacent said trackway, means for driving the conveyer, and means on said conveyer for propelling said carrying and identifying means along the slot 25 whereby they are released from said structure at predetermined points.

38. In a sorting machine, a main trackway carrying and identifying means movable 30 on said trackway, a moving belt ar-

ranged adjacent said main trackway, means on said belt adapted to engage said carrying and identifying means, a feed trackway adjacent the main trackway adapted to hold said carrying and identifying means and 25 automatically operated means for transferring the carrying and identifying means from the feed to the main trackway.

39. In a sorting machine, a trackway, carrying and identifying means slidable on 40 said trackway, a moving conveyer arranged adjacent said trackway, means on said conveyer adapted to engage said carrying and identifying means, mechanism for feeding said carrying and identifying means to said trackway and means for operating said feed mechanism. 45

40. In a sorting machine a structure having a slot, carrying and identifying means movable in said slot, an endless conveyer adjacent said structure, means on said conveyer adapted to engage said carrying and identifying means and means for driving said conveyer. 50

In testimony whereof I affix my signature, 55
in presence of two witnesses.
